APPARATUS FOR THE CONTROL OF HIGHWAY CROSSING SIGNALS

Paul H. Crago, Wilkinsburg, Pa., assignor to The Union Switch & Signal Company, Swissvale, Pa., a corporation of Pennsylvania

Application April 30, 1938, Serial No. 205,301

13 Claims. (Cl. 246—126)

My invention relates to apparatus for the control of highway crossing signals, and more particularly to apparatus for the control of highway crossing signals for electric railways.

5 A feature of my invention is the provision of novel and improved highway crossing signal control apparatus wherewith a loss of protection due to a temporary failure of power is avoided. Other features and advantages of my invention will 10 appear as the specification progresses.

I shall describe several forms of apparatus embodying my invention, and shall then point out the novel features thereof in claims.

15 In the accompanying drawings, Figs. 1, 2, 3, 4 and 5 are diagrammatic views respectively of five different forms of apparatus which embody my invention. Similar reference characters refer to similar parts in each of the several views.

20 Referring to Fig. 1, the reference characters *1a* and *1b* designate the track rails of a stretch of single track electric railway which is provided with a propulsion current supply conductor *2*, such as a trolley wire or third rail, adaptable to contact by a suitable train carried current collecting device, such as a trolley wheel or third rail shoe not shown. In accordance with usual 25 practice, the conductor *2*, when a trolley wire, is supported substantially above the center line of the track at the necessary height. To aid in describing my invention, I shall assume the conductor *2* to be the usual trolley wire. In Fig. 1, as well as in the other drawings, the conductor *2* is illustrated at one side of the track rails for the sake of clarity. It will also be understood, of course, that conductor *2* is connected with one terminal of a source of propulsion current, such as a generator not shown, and the track rails serve as the return path for the propulsion current.

30 This stretch of railway of Fig. 1 is intersected by a highway *H*, adjacent which a highway crossing signal *S* is located. The type of highway crossing signal is immaterial, and as here provided the signal *S* comprises a green light *G* and two red lights *R* and *1R*, the green light *G* being normally illuminated to indicate a clear signal when no railway traffic is approaching the intersection, and the red lights *R* and *1R* being alternately and periodically illuminated to indicate 35 stop to highway users when a train or car is approaching the intersection on the railway. The signal *S* is positioned to be displayed to highway traffic approaching the intersection from one direction. In practicing my invention, a second

signal similar to signal *S* would be located at the intersection and positioned to be displayed to highway traffic approaching the intersection from the other direction. This second signal is not shown for the sake of simplicity since its control would be the same as that of signal *S*, the control of signal *S* being fully described hereinafter.

5 *Four traffic governed devices or contactors are associated with this stretch of railway at selected points. These contactors are preferably alike, and in this instance their construction is that of standard practice for trolley contactors. As viewed in Fig. 1, the contactors *C1* and *C2* are positioned at selected points to the left and right, respectively, of the intersection. The distance 10 the contactors *C1* and *C2* are located from the highway is in each case such as to provide satisfactory warning operation of the signal *S* in response to railway traffic approaching the intersection in the respective directions. To provide 15 the so-called overlap control for the signal *S*, a contactor *C3* is positioned adjacent the intersection on the side opposite the contactor *C1*, and a contactor *C4* is positioned adjacent the intersection on the side opposite the contactor *C2*. In 20 other words, a car approaching the intersection from the left, as viewed in Fig. 1, initiates the 25 warning operation of signal *S* in passing the contactor *C1*, and the warning operation is discontinued when the car passes over the highway and 30 operates the contactor *C3*. A car approaching the intersection from the right initiates the 35 warning operation of the signal in passing the contactor *C2*, and the warning operation is discontinued when the car passes over the intersection and operates the contactor *C4*.*

Looking at contactor *C1*, for example, it comprises two contact members *3* and *9* which are juxtaposed with contact member *3* more remote from the intersection. The contact members *3* and *9* are each spaced from the conductor *2* to be normally free from contact therewith. A trolley wheel of a car or vehicle bridges between the conductor *2* and the members *3* and *9* so that current from conductor *2* is applied to the members, current being applied first to member *3* and then to member *9* when a car approaches the intersection, the trolley wheel engaging the member *9* before it leaves the member *3*. For a car receding from the intersection, that is, moving from right to left in Fig. 1, current is first applied to member *9* and then to member *3* of the contactor *C1*. In a similar manner, the contactor *C2* comprises two juxtaposed contact members *5* 55

and 11, the member 5 being more remote from the intersection so that a trolley wheel of a car approaching the intersection applies current first to member 5 and then to member 11, but a car receding from the intersection causes current to be applied first to member 11 and then to member 5. Again, the contactor C3 comprises two contact members 20 and 36, and the contactor C4 comprises two contact members 22 and 28, current being successively applied to the two contact members of contactors C3 and C4 in accordance with the direction in which a trolley wheel passes thereover in the manner similar to that described for contactors C1 and C2. The contactors C3 and C4 are located on opposite sides of the highway and hence are spaced apart at least the distance equal to the width of the highway.

It will be understood, of course, that my invention is not limited to trolley contactors. The important feature of these contactors so far as my present invention is concerned is the fact that each comprises two contact members to which current is supplied successively and momentarily in response to a car passing thereover, the order in which current is supplied to the two contact members being in accordance with the direction of the passing car. For example, in railways other than electric railways, the contact members 3 and 9 of contact C1 could be actuated by the leading wheel of a passing train, and the source of current could be any suitable wayside source.

To distinguish between cars approaching the intersection and cars receding from the intersection, a first directional device is associated with the first and second contactors C1 and C2, and a second directional device is associated with the third and fourth contactors C3 and C4. These directional devices may take different forms, several being well known. As provided in Fig. 1, the first directional device comprises a first relay N1 and a second relay N2, each of which when energized is effective to prevent the other relay from being energized. Looking at relay N1, an energizing or pick-up circuit extends from contact member 3 of contactor C1 and wire 4 in multiple with contact member 5 of contactor C2 and line wire 6, thence over wire 15, back contact 7 of relay N2, winding of relay N1, resistor R1 and wire 8 to the track rail 1b. A stick circuit for relay N1 includes contact member 9 of contactor C1 and wire 10 in multiple with contact member 11 of contactor C2 and line wire 12, thence over wire 13, front contact 14 and winding of relay N1, resistor R1, wire 8 and to track rail 1b. The energizing or pick-up circuit for relay N2 consists of the same elements as the stick circuit for relay N1 up to wire 13, thence over back contact 16 of relay N1, winding of relay N2, resistor R1, wire 8 and to the track rail 1b. A stick circuit for relay N2 includes the previously traced pick-up circuit for relay N1 up to wire 15, thence over front contact 17 and winding of relay N2, resistor R1, wire 8 and to the track rail 1b. With relay N1 picked up, closing front contact 18, a resistor R2 is connected across the winding of the relay to form a snubbing circuit to provide a slow release period for the relay. Likewise, with relay N2 picked up, closing front contact 19, the resistor R2 is connected across the winding of relay N2 to provide the relay N2 with a slow release period. It follows that when a car approaches the intersection from the left and operates the contactor C1 by engaging contact member 3, or approaches the intersection from the right and op-

erates contactor C2 by engaging contact member 5, a first impulse of current is supplied from conductor 2 to the relay N1 to pick up the relay N1. Then, when the car engages contact member 9 or contact member 11, as the case may be, the relay N1 is still supplied with current over its stick circuit, the relay N1 being held picked up for its slow release period subsequent to such energization by virtue of the associated snubbing circuit. The relay N2 is not affected by a car approaching the intersection from either direction, since its circuit is held open at back contact 16 of relay N1. When a car is receding from the intersection to the left and engages contact member 9 of contactor C1 first, or is receding from the intersection to the right and engages contact member 11 of contactor C2 first, a first impulse of current is supplied from conductor 2 to the relay N2, and relay N2 is picked up. Then current is supplied to relay N2 over its stick circuit when the car engages contact member 3 or contact member 5, as the case may be. The relay N1 is not affected by a car receding from the intersection because the circuit for relay N1 is held open at back contact 7 of relay N2.

The second directional device, associated with the contactors C3 and C4, comprises two relays N3 and N4, each of which is effective when picked up to prevent the other relay from being energized, and which relays are controlled over pick-up and stick circuits similar to the circuits described for relays N1 and N2 of the first directional device. When a car moving from left to right passes over the intersection and engages contact member 20 of contactor C3, or when a car moving from right to left passes over the intersection and engages contact member 22 of contactor C4, a first impulse of current is supplied from conductor 2 through contact member 20 and wire 21, or through contact member 22 and wire 23, as the case may be, wire 24, back contact 25 of relay N4, winding of relay N3, resistor R3, wires 26 and 8, and track rail 1b, and relay N3 is picked up. With relay N3 picked up, a second impulse is supplied to the relay over its stick circuit when the member 36 of contactor C3 is engaged by the car moving to the left, or when the member 28 of contactor C4 is engaged by the car moving to the right. The stick circuit for relay N3 involves member 36 and wire 27 in multiple with member 28 and wire 29, wire 30, front contact 31 and winding of relay N3, resistor R3, wires 26 and 8, and track rail 1b. With relay N3 picked up, closing front contact 34, a resistor R4 is connected across the winding of relay N3 to provide the relay with a snubbing circuit so that the relay is slow releasing in character.

A pick-up circuit for the relay N4 includes the same elements as the stick circuit for relay N3 up to wire 30; thence it extends over back contact 32 of relay N3, winding of relay N4, resistor R3, wires 26 and 8, and the track rail 1b. The stick circuit for relay N4 includes the same elements as the pick-up circuit for relay N3 up to wire 24, thence over front contact 33 and winding of relay N4, resistor R3, wires 26 and 8, and track rail 1b. The resistor R4 is connected across the winding of relay N4 over front contact 35 of relay N4 to provide this relay with a slow release characteristic. It is to be seen, therefore, that when a car approaches the intersection from the left and passes over the contactor C4, or approaches the intersection from the right and passes over the contactor C3, a first impulse of current is supplied to the winding of relay N4 as the trolley wheel of

the car engages contact member 28 or contact member 36, as the case may be, and a second impulse of current is supplied to the relay N4 over its stick circuit as the trolley wheel engages the contact member 22 or contact member 20. With relay N4 picked up in response to a car approaching the intersection, the relay N3 is prevented from being energized due to the fact that the circuit for relay N3 is held open at back contact 25 of relay N4. The manner whereby these two directional devices control the highway crossing signal S will appear hereinafter.

The immediate control of signal S is effected by a polarized relay HR, which relay is in turn controlled by the two directional devices, relay HR being energized at one polarity when a train is approaching the intersection and being energized at the opposite polarity when the train is receding from the intersection. The relay HR is provided with a normal energizing winding NW and a reverse energizing winding RW, the arrangement being such that when current is supplied to the normal winding NW the polar contact members 37 and 38 of the relay are operated to the left-hand position, as viewed in Fig. 1. When current is supplied to the reverse winding RW, the relay HR is energized to move its polar contact members 37 and 38 to the right-hand position to engage reverse polar contacts 39 and 40, respectively. The polarized relay HR is preferably characterized by the fact that the stroke of its polarized armature will be completed if energy is applied to either winding for a long enough interval to open the polar contacts in the last position. In other words, when an impulse of current is supplied to winding RW or NW for an interval long enough to move the polarized armature from its last position, the armature moves to its other extreme position although the energizing current ceases. A relay which may be made to operate in the manner just described is disclosed and claimed in Letters Patent of the United States No. 1,790,671, granted to Branko Lazich on February 3, 1931, for Electrical relays. In order to cause the relay to operate in the intended manner it is only necessary to provide the relay cores with an additional winding similar to that shown in the patent as will be readily understood by those skilled in the art.

An energizing circuit for relay HR can be traced from conductor 2 over wire 41, front contact 42 of relay N1, wire 43, reverse winding RW, a resistor R5, wires 44, 26 and 8, and to the track rail 1b. Consequently, when relay N1 is picked up for a brief interval in response to the contactor C1 or C2 being operated by a car approaching the intersection in the manner explained hereinbefore, the relay HR is supplied with current which flows in the winding RW of the relay, and the polar contact members 37 and 38 are operated to engage the respective reverse polar contacts 39 and 40.

A holding circuit which is effective to supply current to winding RW is provided so that relay HR, once operated to its reverse position, is effectively energized to pick up its neutral armature. This holding circuit involves wire 45 connected with conductor 2, reverse polar contacts 38-40 and 37-39 in series, wire 46, back contacts 47 and 48 of relay N3 in series, wires 49 and 43, winding RW, resistor R5, wires 44, 26 and 8, and the track rail 1b. It follows that when current is momentarily supplied to the winding RW of relay HR in response to a car approaching the in-

tersection to pick up relay N1, the polarized armature of relay HR is moved to its reverse position and the relay HR is retained energized at its reverse position and its neutral armature is picked up by virtue of its holding circuit, which holding circuit includes back contacts 47 and 48 of the relay N3 of the second directional device. It will be understood, of course, that the impulse of current supplied to winding RW over the first traced energizing circuit, including front contact 42 of relay N1, may be of sufficient duration to cause relay HR to pick up its neutral armature, but this impulse of current need be only of sufficient duration to move the polar contact members 37 and 38 of the relay away from their normal position, the polar contact members 37 and 38 completing their reverse movement by virtue of the characteristics of the relay, and the holding circuit being effective to energize the relay to operate its neutral armature.

Another energizing circuit for relay HR can be traced from conductor 2, wire 45, reverse polar contacts 38-40 and 37-39 in series, wire 46, front contacts 66 and 67 of relay N3 in series, wire 68, normal winding NW, resistor R5, wires 44, 26 and 8, and to the track rail 1b. Consequently, with the relay HR in its reverse position and the relay N3 of the second directional device picked up in the manner pointed out hereinbefore, an impulse of current is supplied to the winding NW to restore to relay HR to its normal position.

The lamp G of signal S is controlled over a back neutral contact of relay HR, and the lamps R and 1R of signal S are controlled over front neutral contacts of relay HR through the medium of a flasher relay FR, which flasher relay may be of any of the well-known constructions. It is deemed sufficient for this application to point out that the contact member 56 of relay FR is biased to a mid position, that is, the position illustrated by the solid line in Fig. 1, and is operated between two extreme positions, illustrated by dotted lines, at a predetermined frequency of, say, 30 times per minute when the winding of the relay FR is energized. As here shown, the contact member 56 engages a contact 57 at both its mid and left-hand positions and engages a contact 58 at its right-hand position. For illuminating the lamp G, current is supplied from conductor 2 over wire 45, four back neutral contacts 50, 51, 52 and 53 of relay HR in series, a resistor R6, wire 54, lamp G, wires 55 and 8, and to the rail 1b. With relay HR picked up, closing its front neutral contacts, current is supplied from conductor 2 over wire 45, front neutral contacts 59, 60, 61 and 62 in series, wire 63, a resistor R7, winding of flasher relay FR, wires 44, 26 and 8, and to track rail 1b, and the flasher relay FR is operated. During each interval, the contact 56-57 of flasher relay FR is closed, the lamp 1R is short-circuited, and the lamp R is illuminated by current flowing over the same circuit traced for relay FR up to wire 63, and thence over a resistor R8, contact 56-57, wire 64, lamp R and wires 55 and 8 to the track rail 1b. During each interval the contact 56-58 of relay FR is closed, the lamp R is short-circuited and the lamp 1R is illuminated by current flowing from wire 63 over resistor R8, wire 65, lamp 1R, wire 64, contact 56-58, wires 44, 26 and 8, and to the rail 1b.

In describing the operation of the apparatus of Fig. 1, I shall consider the operating steps effected in response to a car moving from left to right. At the start, the lamp G of signal S is illuminated by current supplied over the back

contact 53 of relay HR. The trolley wheel of the car successively engages the contact members 3 and 9 of contactor C1, and the relay N1 is energized for a brief interval, closing its front contact 42. The closing of front contact 42 causes current to be supplied to the reverse winding RW of relay HR, and the relay is operated to its reverse position, closing reverse polar contacts 37—39 and 38—40. Relay HR is retained energized in its reverse position over its holding circuit subsequent to the time the car passes the contactor C1, so that the neutral armature of relay HR is picked up, opening the circuit for lamp G and closing at its front contacts the circuit for supplying current to the flasher relay FR and in turn to the lamps R and !R of signal S. As the car passes the contactor C4 in approaching the intersection, the relay N4 is picked up for an interval to prevent operation of relay N3, so that the relay HR remains energized to operate the lamps R and !R of signal S while the car passes over the intersection. The car, after passing over the intersection and receding from the crossing, successively engages the members 20 and 36 of contactor C3, so that the relay N3 is picked up for a brief interval, and relay N3 on picking up opens the holding circuit for relay HR and closes the energizing circuit to winding NW of relay HR. Current supplied to the normal winding NW causes the polarized armature of relay HR to be moved back to its normal position where the reverse polar contacts are open, and hence, when the car passes the contactor C3, the relay HR is deenergized and releases its neutral armature. With relay HR deenergized and its neutral armature released, the lamps R and !R are extinguished and the lamp G is again illuminated. This car moving from left to right engages first the contact member 11 and then the contact member 5 of the contactor C2, and the relay N2 of the first directional device is picked up to prevent operation of the relay N1, with the result that the relay HR, and in turn the signal S, are not affected by the car receding from the intersection.

A car moving from right to left, on passing contactor C2 engages contact member 5 and then contact member 11, so that relay N1 is picked up, closing front contact 42. Closing of front contact 42 causes current to be supplied to winding RW, as previously described, and relay HR is operated to close its reverse polar contacts 37—39 and 38—40. Relay HR is retained energized at its reverse position by virtue of its holding circuit, so that its neutral armature is picked up and the lamp G is extinguished and the lamps R and !R are flashed to warn the highway users of the approach of the car. This car engages contact members 36 and 20 of contactor C3 in the order named, and relay N4 is picked up to prevent operation of relay N3, and the operation of the signal S is continued while the train passes over the intersection. When the car recedes from the crossing, it engages contact members 22 and 28 of contactor C4 in the order named, and the relay N3 is picked up for an interval to open the holding circuit of relay HR and to close the energizing circuit through the normal winding NW. With relay HR thus restored to its normal position, its neutral armature is released so that the operation of the lamps R and !R is stopped and the lamp G is again illuminated. The car moving to the left away from the crossing engages

the contact members 9 and 3 of contactor C1 in the order named, and relay N2 is picked up to prevent operation of relay N1.

It should be pointed out that in the event a car moving from left to right passes contactor C1 to operate the relay HR to its reverse position and then there is a temporary failure of power to the conductor 2 while the car is between contactor C1 and the intersection, the relay HR is deenergized during the interval of power failure, but relay HR is at once reenergized and picked up over its holding circuit and operation of the signal S is restored as soon as power is restored to conductor 2. A similar action for relay HR is effected in the event of a temporary loss of power while a car moving from right to left approaches the intersection. The resistor R5 interposed in series with the windings RW and NW is relatively large and thereby reduces the time constant of the circuit including these windings, with the result that a relatively rapid operation of the polarized relay is effected. Furthermore, the apparatus is restored to its normal position as soon as a car moving from left to right passes the contactor C3, and a second and following car passing the contactor C1 will operate the signal S the same as the first car. Likewise, the apparatus is conditioned to operate for a second car moving from right to left, as soon as the first car passes the contactor C4.

In Fig. 2 the track rails 1a and 1b of a single track electric railway are intersected by a highway H, at which a highway crossing signal S is located, the same as in Fig. 1. The contactors C1 and C2 are located similarly to the contactors C1 and C2 of Fig. 1, and these contactors operate pick-up and stick circuits for the relays N1 and N2 of the first directional device the same as described in Fig. 1 except for the fact that a resistor R9 is permanently connected across the winding of relay N1 and a resistor R10 is permanently connected across the winding of relay N2 to provide these relays with desirable operating characteristics.

In Fig. 2 a contactor C5 having a single contact member 69 is located preferably at the intersection and controls a relay N5 over a simple circuit including member 69, winding of relay N5, a resistor R11 and wire 70 to the track rail 1b. Hence, relay N5 is momentarily energized and picked up whenever the trolley wheel of a car engages the member 69, irrespective of the direction in which the car is moving. It is to be noted that the contact member 69 of contactor C5 would be somewhat greater in length than the contact members of the other contactors.

The polarized relay HR of Fig. 2 is the same as in Fig. 1, and current is supplied to its reverse winding RW over a front contact 42 of relay N1 for operating the relay to its reverse position. The holding circuit for relay HR of Fig. 2 extends from conductor 2, wires 41 and 71, reverse polar contacts 38—40 and 37—39 in series, back contacts 72 and 73 of relay N5 in series, wires 78 and 43, reverse winding RW, resistor R5, wires 74 and 70, and to the rail 1b. The energizing circuit including the normal winding NW of relay HR can be traced from conductor 2 over wires 41 and 71, reverse polar contacts 38—40 and 37—39, front contact 75 of relay N5, winding NW, a resistor R12, wires 74 and 70, and to the track rail 1b. A resistor R13 is shown connected in shunt with the normal winding NW to avoid opening the full trolley voltage when

the circuit including winding NW is interrupted at the polar contacts of the relay.

The relay HR of Fig. 2 controls the signal S in substantially the same manner as in Fig. 1.

5 Normally, the lamp G is illuminated to display a clear signal to the highway users by virtue of a circuit extending from conductor 2 over wires 41 and 71, resistor R6, back contact 76 of relay HR, lamp G and wires 55 and 70 to the track rail 1b.

Assuming a car approaches the intersection from the left, the relay N1 is picked up for a brief interval due to the trolley wheel making contact successively with the members 3 and 9

15 of the contactor C1. Closing front contact 42 of relay N1 causes current to be supplied to the winding RW of relay HR so that relay HR is operated to its reverse position and the holding circuit for the relay closed at the reverse polar

20 contacts 38-40 and 37-39. With relay HR energized over its holding circuit, its neutral armature is picked up, opening back contact 76 interposed in the circuit for lamp G, and closing front contact 77 interposed in the circuit for the

25 flasher relay FR and lamps R and 1R. The circuit for the flasher relay FR involves wires 41 and 71, reverse polar contacts 38-40 and 37-39, back contacts 72 and 73 of relay N5, wires 78 and 43, front contact 77, resistor R7, winding of

30 relay FR, and wires 74 and 78 to the track rail 1b. With relay FR operating, current is supplied alternately to the lamps R and 1R, the same as described in Fig. 1. As the car is passing over the highway and its trolley wheel engages contact member 69 of contactor C5, current is supplied to relay N5, and the relay is picked up momentarily to open the back contacts 72 and 73 interposed in the holding circuit for relay HR and to close front contact 75 interposed in the

35 energizing circuit for the normal winding NW. This momentary energization of winding NW causes the polar armature of relay HR to be operated to its normal position, with the result that the relay HR is deenergized and releases its neutral armature when the relay N5 releases.

The relay FR and the lamps R and 1R are now without current and the lamp G is again illuminated. This car moving to the right engages contact members 11 and 5 of contactor C2 in

40 the order named, and relay N2 is picked up to prevent the operation of relay N1. It is to be noted that the apparatus is restored to its normal position as soon as the car passes over the intersection, and hence the relay HR and the

45 signal S are operated by a second or following car approaching the highway H from the left and operating the contactor C1.

The operation of the apparatus of Fig. 2 for a car moving from right to left over the intersection is substantially the same as for the car moving from left to right, and the operation effected by a car moving from right to left need not be described in detail.

In Fig. 2, it is clear that, in the event of a loss of propulsion current just after the relay HR is operated to its reverse position, the relay HR is deenergized during the interval the propulsion current is interrupted and is reenergized over its holding circuit as soon as the propulsion

50 power is restored to the conductor 2. That is to say, the directional control is not released in the event of a loss of power and the warning operation is reestablished as soon as power is restored.

55 Referring now to Fig. 3, a single track electric

railway is intersected by a highway having a highway crossing signal S located at the intersection, and has associated therewith contactors C1, C2 and C5, the same as in Fig. 2. In Fig. 3, the relays N1 and N2 of the first directional control device are provided with pick-up and stick circuits controlled by the contactors C1 and C2, the same as in Fig. 1 except the contact member 69 of contactor C5 is connected by a wire 80 with the wire 12 so that relay N2 is momentarily energized when the trolley wheel of a car passing over the intersection engages the member 69, relay N2 being energized irrespective of the direction the car moves over the intersection.

10 It is believed that the circuits and apparatus of Fig. 3 will be best understood by a description of the operation of the apparatus. Normally,

15 the lamp G is illuminated by current supplied from conductor 2 over wires 41 and 81, back contact 82 of relay HR, resistor R6, lamp G, wires 55 and 78, and to the rail 1b. A car approaching

20 the intersection from the left successively engages members 3 and 9 of contactor C1, and the relay N1 is picked up for a brief interval. The closing of front contact 42 of relay N1 causes

25 current to be supplied to the reverse winding RW of relay HR the same as in the previous cases, and relay HR is operated to move its polarized armature to the reverse position where its reverse polar contacts 37-39 and 38-40 are

30 closed. In Fig. 3, a holding circuit for relay HR is provided which extends from conductor 2 over wires 41 and 81, reverse polar contacts 38-40 and 37-39 in series, wire 87, back contacts 88 and 89 of relay N2 in series, winding RW, resistor R5, wires 74 and 78, and to the rail 1b. Thus,

35 the relay HR is operated to its reverse position, and its neutral armature is picked up in response to the car passing over the contactor C1. The back contact 82 of relay HR is now open to

40 remove current from lamp G, and the front contacts 83, 84, 85 and 86 of relay HR are closed to complete a circuit for the flasher relay FR and the lamps R and 1R, so that relay FR is

45 operated and the lamps R and 1R are flashed to provide a warning indication of the approach of the car to the intersection.

As the car passes over the intersection and its trolley wheel engages the contact member 69 of contactor C5, current is supplied to relay N2 and relay N2 is picked up for a brief interval.

50 The picking up of relay N2 opens back contacts 88 and 89 interposed in the holding circuit for relay HR and closes front contacts 90 and 91 so that current is supplied to the winding NW,

55 the circuit being the same as the holding circuit up to wire 87, thence over front contacts 90 and 91 in series, winding NW, resistor R5, wires 74 and 78, and to the rail 1b. With the winding NW momentarily energized, the relay HR operates its polar contact members 38 and 37 back

60 to the normal position, with the result that when the relay N2 is released the relay HR is without current and its neutral armature is released so

65 that the lamps R and 1R are extinguished and the lamp G is again illuminated. This car on receding from the intersection successively engages members 11 and 5 of contactor C2 in the

70 order named, and the relay N2 is picked up to prevent operation of the relay N1.

A car moving from right to left in Fig. 3 causes a corresponding operation of the apparatus, and this operation need not be described in detail.

75 It should be noted that with the apparatus constructed as shown in Fig. 3, a temporary loss of

power from conductor 2 after a car has passed over contactor C1 or C2 in approaching the intersection will, of course, cause the relay HR to be deenergized, but the relay HR is at once reenergized over its holding circuit and the warning operation of the signal S is restored when power is restored to conductor 2.

In Fig. 4, a single track electric railway is intersected by a highway H having a highway crossing signal located adjacent thereto the same as in the previous cases. The contactors C1, C2 and C5 of Fig. 4 are disposed with respect to the highway the same as in Figs. 2 and 3. The polarized relay HR of Fig. 4 is operated directly by the contactors C1, C2 and C5 with directional control effected through the medium of a single neutral relay N6.

The apparatus of Fig. 4 can best be understood by a description of its operation. Normally, the lamp G of signal S is illuminated by current supplied from conductor 2 over wire 92, back contact 93 of relay HR, resistor R6, lamp G, wires 55 and 70, and to the track rail 1b. A car approaching the intersection from the left first engages the contact member 3 of contactor C1, and in so doing causes current to be supplied to the reverse winding RW of relay HR, the circuit involved including wires 4 and 15, back contact 94 of relay N6, wire 95, reverse winding RW, a resistor R14, wires 74 and 70, and track rail 1b. I have found that by proportioning the resistor R14 and the winding RW so that the relay HR receives only its normal ampere-turn energization the time constant of the circuit is relatively low and operation of the polarized armature of relay HR in less than 0.05 second is effected. With the parts thus proportioned, the relay HR is energized to reverse its polar armature although the winding RW is energized but for the brief interval the contact member 3 is bridged by the trolley wheel. It will be recalled that relay HR is characterized by the fact that its polar contact members, once started from their last position, will move to their other extreme position notwithstanding the energizing current ceases. With relay HR reversed, current is supplied over a holding circuit which in this case includes conductor 2, wire 92, reverse polar contact 96-97, reverse winding RW, resistor R14, wires 74 and 70, and to the track rail 1b, and relay HR is effectively energized to pick up its neutral armature. As the polarized armature of relay HR is reversed before the contact member 9 of contactor C1 is engaged by the trolley wheel, a possible circuit, to be later described, for energizing relay N6 is opened at the normal polar contact 105-106 of relay HR. The opening of back contact 93 of relay HR extinguishes the lamp G, and the closing of front contacts 98, 99, 100 and 101 causes current to be supplied to the flasher relay FR, which relay is operated to alternately flash the lamps R and IR in the manner described for Fig. 1.

This car on moving over the intersection to engage contact member 69 of contactor C5 causes current to be supplied to the winding NW, the circuit including wire 102, the reverse polar contact 103-104 and a resistor R15. The resistor R15 and the winding NW are proportioned to provide an ampere-turn energization greater than that effected by the holding circuit energizing winding RW, and also to effect a relatively low time constant for the circuit. The polarized armature of relay HR is therefore returned to its normal position in response to the

car engaging the contact member 69 of contactor C5. With relay HR restored to its normal position, its holding circuit is open at the reverse polar contact 96-97 and relay HR is deenergized to release its neutral armature subsequent to the car passing beyond the contactor C5. The lamps R and IR are now dark and the lamp G is illuminated. This car moving to the right next engages the contact member 11 of contactor C2, and current is supplied from conductor 2 through the contact member 11, wire 12, wire 107, normal polar contact 105-106, wire 108, winding of relay N6, a resistor R16, wire 70, and to the track rail 1b, and the relay N6 is picked up. Relay N6 is supplied with current over a stick circuit when the contact member 5 of contactor C2 is next engaged by the car moving away from the intersection, the stick circuit involved including wires 6 and 15, and front contact 125 of relay N6. It is to be seen, therefore, that no current is supplied to relay HR when the car moves over the contactor C2 in moving away from the intersection due to the directional control effected by relay N6. The operation of the apparatus of Fig. 4 for a car moving from the right to the left is correspondingly similar to that just described for the car moving from left to right, and further detailed description of the operation is unnecessary. It is to be noted, however, in connection with the apparatus of Fig. 4 that a loss of power to the conductor 2 deenergizes the relay HR, but relay HR is reenergized and the warning operation of signal S is reestablished immediately following the restoring of power to the conductor 2.

In the form of the invention disclosed in Fig. 5 the apparatus is the same as in Fig. 3 except that the polarized relay HR is normally energized over a holding circuit and the relay is picked up to close its front neutral contacts. To be explicit, current is normally supplied from conductor 2 over a holding circuit including wires 41 and 81, normal polar contacts 109-110 and 111-112 in series, wire 113, back contacts 114 and 115 of relay N1 in series, wire 116, normal winding NW, resistor R5, wires 74 and 70, and track rail 1b. The closing of front contact 117 of relay HR completes a circuit easily traced from lamp G, and lamp G is normally illuminated. On the assumption a car approaches the intersection from the left, the relay N1 is picked up for an interval due to the successive impulses supplied when the trolley wheel engages contact members 3 and 9 of contactor C1. With relay N1 picked up, opening back contacts 114 and 115, the holding circuit for relay HR is opened and a circuit is formed for winding RW at the front contacts 119 and 118 of relay N1, so that current flows from conductor 2 over wires 41 and 81, normal polar contacts 109-110 and 111-112, wire 113, front contacts 118 and 119, wire 120, reverse winding RW, resistor R5, wires 74 and 70, and track rail 1b. The polarized armature of relay HR is now operated to its reverse position so that when relay N1 is released subsequent to the car passing over contactor C1 the relay HR is deenergized to release its neutral armature. Opening of front contact 117 of relay HR extinguishes lamp G, and the closing of back contacts 121, 122, 123 and 124 in series completes a circuit easily traced for supplying current to the flasher relay FR and in turn to the lamps R and IR. Contact of the trolley wheel with the member 69 of contactor C5 as the car passes over the intersection supplies current to relay N2 in the same manner

as described for Fig. 3, and relay N2 is picked up for a brief interval. An energizing circuit is now formed from conductor 2 over wires 41 and 126, front contact 127 of relay N2, wire 116, normal winding NW, resistor R5, wires 74 and 70, and track rail 1b, and the polarized armature of relay HR is operated to its normal position to close the normal polar contacts 109—110 and 111—112. Relay HR is now energized over its holding circuit, with the result that the flasher relay FR and lamps R and 1R are deenergized and the lamp G is again illuminated. As the car moves to the right and passes over the contactor C2, relay N2 is picked up in the same manner as described for Fig. 3, but relay HR is unaffected by the current supplied to winding NW over front contact 127 since relay HR is now energized by its holding circuit. Consequently, the signal S is not affected as this car moving to the right recedes from the intersection. The operation of the apparatus of Fig. 5 for a car moving from right to left is correspondingly similar to that just described for a car moving from left to right, and further detailed description of the operation of the apparatus is unnecessary.

Although I have herein shown and described only five forms of apparatus embodying my invention, it is understood that various changes and modifications may be made therein within the scope of the appended claims without departing from the spirit and scope of my invention.

Having thus described my invention, what I claim is:

35. 1. In combination, a railway track intersected by a highway, a highway crossing signal located at the intersection, a first traffic controlled device located to one side of the intersection, a second traffic controlled device located adjacent the intersection, a relay having a polar armature, circuit means controlled by said first device to energize said relay at one polarity when a vehicle passes the first device, other circuit means controlled by said second device to energize said relay at the other polarity when a vehicle passes the second device, a holding circuit including polar contacts of said relay and controlled by a selected one of the devices to energize the relay at a selected polarity, and operating means governed by the relay for operating the signal.

50. 2. In combination, a railway track intersected by a highway, a highway crossing signal located at the intersection, a first traffic controlled device located to one side of the intersection, a second traffic controlled device located adjacent the intersection, a polarized relay normally conditioned with its polar armature at a selected one of its positions, a first circuit operative while a vehicle is passing said first device to supply an impulse of current to energize the relay at the polarity required to move the polar armature away from said selected position, a second circuit operative while a vehicle is passing said second device to supply an impulse of current to energize the relay at the polarity required to move the polar armature away from the position opposite said selected position, a holding circuit including a polar contact of the relay for at times energizing the relay to pick up its neutral armature, and operating means controlled by the neutral armature for operating the signal.

65. 3. In combination, a railway track intersected by a highway, a highway crossing signal located at the intersection, a first traffic controlled device located to one side of the intersection and

including a pair of juxtaposed contact members, a second traffic controlled device located adjacent the intersection and including a contact member, a polarized relay having a normal energizing winding and a reverse energizing winding, directional means controlled by said pair of contact members when operated by a train approaching the intersection to supply an impulse of current to said reverse winding and to prevent such supply of current when operated by a train receding from the intersection, a holding circuit including a selected one of the relay windings and a corresponding polar contact of the relay for at times energizing the relay to operate its neutral armature, other circuit means controlled by the contact member of said second device when operated by a train to supply an impulse of current to said normal winding, and operating means controlled by the neutral armature of the relay for operating the signal.

20. 4. In combination, a railway track intersected by a highway, a highway crossing signal located at the intersection, a first contactor located to one side of the intersection, a second contactor located adjacent the intersection, a polarized relay, a first circuit means controlled by said first contactor when operated by a car approaching the intersection to energize the relay at reverse polarity, a holding circuit including a reverse polar contact of the relay to energize the relay at reverse polarity, a second circuit means controlled by said second contactor when operated by a car to effectively energize the relay at normal polarity, and operating means controlled by the neutral armature of the relay for operating the signal.

25. 5. In combination, a railway track intersected by a highway, a highway crossing signal located at the intersection, a first contactor located to one side of the intersection, a second contactor located adjacent the intersection, a polarized relay having a normal energizing winding and a reverse energizing winding, a first circuit controlled by said first contactor operative to supply an impulse of current to said reverse winding when a car approaching the intersection passes said first contactor, a holding circuit for energizing the relay including said reverse winding and a reverse polar contact of the relay, a second circuit controlled by said second contactor operative to supply an impulse of current to said normal winding while a car passes said second contactor, and operating means controlled by the neutral armature of said relay for operating the signal.

30. 6. In combination, a railway track intersected by a highway, a highway crossing signal located at the intersection, a first contactor located to one side of the intersection, a second contactor located adjacent the intersection, a polarized relay having a normal energizing winding and a reverse energizing winding, a first circuit controlled by said first contactor operative to supply an impulse of current to said reverse winding when a car approaching the intersection passes said first contactor, a holding circuit for energizing the relay including said reverse winding and a reverse polar contact of the relay, other circuit means controlled by said second contactor operative while a car is passing said second contactor to open said holding circuit and to supply an impulse of current to said normal winding, and operating means controlled by the neutral armature of said relay for operating the signal.

7. In combination, a railway track intersected by a highway, a highway crossing signal located at the intersection, a first traffic controlled device located on one side of the intersection and including two contact members disposed with one slightly more remote from the intersection than the other, a second traffic controlled device located on the other side of the intersection and including two contact members disposed with one slightly more remote from the intersection than the other, an additional traffic controlled device located adjacent the intersection and including a contact member, directional means including a first and a second relay, circuit means including a back contact of the second relay to energize the first relay and made operative when the more remote member of either the first or the second device is engaged by a train, other circuit means including a back contact of the first relay to energize the second relay and made operative when the nearer member of either the first or the second device is engaged by a train, a polarized relay having a normal energizing winding and a reverse energizing winding, means including a front contact of said first relay to supply current to said reverse winding, a holding circuit for said polarized relay including a reverse polar contact and the reverse winding of the relay, means to open said holding circuit and to supply current to said normal winding and made operative when the member of said additional device is engaged by a train, and means including neutral contacts of said polarized relay for operating the signal.
8. In combination, a railway track intersected by a highway, a highway crossing signal at the intersection, a first pair of contact members located successively on one side of the intersection, a second pair of contact members located successively on the other side of the intersection, a third pair of contact members located successively adjacent the intersection on the side opposite said first pair, a fourth pair of contact members located successively adjacent the intersection on the side opposite said second pair, a first directional means comprising a first and a second relay each of which is effective when picked up to prevent the other relay from being energized, a second directional means comprising a third and a fourth relay each of which is effective when picked up to prevent the other relay from being energized, means to connect said first relay with the member more remote from the intersection of each of said first and said second pair, means to connect the second relay with the member nearer the intersection of each of said first and said second pair, means to connect the third relay with the member nearer the intersection of each of said third and said fourth pair, means to connect the fourth relay with the member more remote from the intersection of each of said third and said fourth pair, a polarized relay having a normal and a reverse winding, means including a front contact of said first relay to supply current to said reverse winding, a holding circuit to supply current to said reverse winding including a reverse polar contact of the polarized relay and a back contact of said third relay, means including a front contact of the third relay to supply current to said normal winding, and operating means including neutral contacts of the polarized relay to operate the signal.
9. In combination, a railway track intersected by a highway, a highway crossing signal at the intersection, a first pair of contact members located successively on one side of the intersection, a second pair of contact members located successively on the other side of the intersection, an additional contact member located adjacent the intersection, directional means comprising a first and a second relay each of which is effective when picked up to prevent the other relay from being energized, means to connect said first relay with the contact member more remote from the intersection of each of said first and said second pair, means to connect the second relay with the contact member nearer the intersection of each of said first and said second pair, another relay connected with said additional member, a polarized relay having a normal and a reverse winding, means including a front contact of said first relay to supply current to said reverse winding, a holding circuit to supply current to said reverse winding including a reverse polar contact of the polarized relay and a back contact of said other relay, means including a front contact of said other relay to supply current to said normal winding, and operating means including neutral contacts of the polarized relay to operate the signal.
10. In combination, a railway track provided with a propulsion current conductor and intersected by a highway, a highway crossing signal at the intersection, a first contactor located to one side of the intersection and a second contactor located adjacent the intersection and said contactors disposed for operation by the current collector of a passing vehicle, a polarized relay having a normal energizing winding and a reverse energizing winding, means governed by said first contactor when operated to supply current from said conductor to said reverse winding, a holding circuit for said polarized relay including the reverse winding and a reverse polar contact, means governed by said second contactor when operated to open said holding circuit and to supply current from said conductor to said normal winding, and means including neutral contacts of said polarized relay to govern said signal.
11. In combination, a railway track provided with a propulsion current conductor and intersected by a highway, a highway crossing signal at the intersection, a first contactor located to one side of the intersection and a second contactor located adjacent the intersection and said contactors disposed for operation by the current collector of a passing vehicle, a polarized relay having a normal energizing winding and a reverse energizing winding, means governed by said first contactor when operated to connect said reverse winding between said conductor and a track rail, a holding circuit to connect said reverse winding between said conductor and a track rail including a reverse polar contact of the relay and a normally closed contact, means governed by said second contactor when operated to open said normally closed contact and to connect said normal winding between said conductor and a track rail, and means including neutral contacts of the relay to operate the signal.
12. In combination, a railway track intersected by a highway, a highway crossing signal at the intersection, a first pair of contact members located successively on one side of the intersection, a second pair of contact members located successively on the other side of the intersection, an additional contact member located adjacent the intersection, directional means comprising a first and a second relay each of which is effective when picked up to prevent the other relay from being energized, means to connect said first relay with the contact member more remote from the intersection of each of said first and said second pair, means to connect the second relay with the contact member nearer the intersection of each of said first and said second pair, another relay connected with said additional member, a polarized relay having a normal and a reverse winding, means including a front contact of said first relay to supply current to said reverse winding, a holding circuit to supply current to said reverse winding including a reverse polar contact of the polarized relay and a back contact of said other relay, means including a front contact of said other relay to supply current to said normal winding, and operating means including neutral contacts of the polarized relay to operate the signal.

the intersection, directional means comprising a first and a second relay each of which is effective when picked up to prevent the other relay from being energized, means to connect said first relay with the contact member more remote from the intersection of each of said first and said second pair, means to connect said second relay with the contact member nearer the intersection of each of said first and said second pair and to said additional contactor, a polarized relay having a normal and a reverse winding, means including a front contact of said first relay to supply current to said reverse winding, a holding circuit to supply current to said reverse winding including a reverse polar contact of the polarized relay and a back contact of said second relay, means including a front contact of said second relay to supply current to said normal winding, and operating means including neutral contacts of the polarized relay to operate the signal.

13. In combination, a railway track intersected by a highway, a highway crossing signal located at the intersection, a pair of contactors located on one side of the intersection and arranged for successive operation by a train approaching the intersection, a third contactor located adjacent the intersection, a polarized relay having a reverse energizing winding and a normal energizing winding, directional means controlled by said pair of contactors when operated by a train approaching the intersection to supply an impulse of current to said reverse winding, a holding circuit for energizing the relay including said reverse winding and a reverse polar contact of the relay, circuit means controlled by said third contactor to supply an impulse of current to said normal winding when a train passes the contactor, and means including neutral contacts of the relay for controlling the signal.

PAUL H. CRAGO. 20
